[57] CLAIM

The ornamental design for a wide format printer, as shown and described.

DESCRIPTION

FIG. 1 is a top, front, left side perspective view of a wide format printer showing our new design;

FIG. 2 is a top view thereof;

FIG. 3 is a rear view thereof;

FIG. 4 is a left side view thereof;

FIG. 5 is a front view thereof; and,

FIG. 6 is a right side view thereof.

The bottom view of this printer is not seen nor intended to be seen as part of our design.

1 Claim, 6 Drawing Sheets

Fig. 2

FIG. 6
